(57) CLAIM

I claim the ornamental design of a toy horse, as shown and described.

DESCRIPTION

FIG. 1 is a perspective of the toy horse.

FIG. 2 is a right side view of the toy horse.

FIG. 3 is a left side view of the toy horse.

FIG. 4 is a front side view of the toy horse.

FIG. 5 is a back side view of the toy horse.

FIG. 6 is a top view of the toy horse; and,

FIG. 7 is a bottom view of the toy horse.

The broken line showing of the child in FIG. 1 is for illustrative purposes only, and forms no part of the claimed design.

1 Claim, 6 Drawing Sheets
